(57) CLAIM

The ornamental design for a blanket with lower rear foot pouch, as shown and described.

DESCRIPTION

FIG. 1 is a front lower left perspective view of a blanket with lower rear foot pouch showing the claimed design;

FIG. 2 is a rear upper right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective in-use view thereof; and,

FIG. 10 is a rear left side perspective in-use view thereof.

The broken lines in the figures show portions of the “blanket with lower rear foot pouch” that form no part of the claimed design.

1 Claim, 7 Drawing Sheets
